LOCK BOLT STRUCTURE

Robert C. Cerf, Jr., Los Angeles, Calif., assignor to
Hollymade Hardware Manufacturing Company,
Los Angeles, Calif., a corporation of California

Application May 9, 1949, Serial No. 92,185

4 Claims. (Cl. 292—2)

1

This invention relates to a lock bolt structure and in particular to means for attaching a retractor bar to a latch bolt.

One object of the invention is to provide a simple construction for a lock bolt structure including the latch bolt and the elongated retractor bar. Another object is to provide means for rigidly connecting a latch bolt and a latch retractor bar. A further object is to provide a latch bolt which may be formed in simple draw molds with a minimum of machine finishing which may be rigidly attached to a retractor bar made from a metal stamping.

These and other objects are attained by my invention which will be understood from the following description, reference being made to the accompanying drawing which forms a part hereof, in which:

Figure 1 is a top plan view with parts broken away and shown in section, showing a spring lock or latch bolt assembly including the latch bolt and the attached retractor bar structure of my invention;

Figure 2 is a sectional view taken on the line 2—2 of Figure 1;

Figure 3 is a cross-sectional view taken on the line 3—3 of Figure 2;

Figure 4 is a perspective disassembly of my latch bolt and retractor bar structure;

Figure 5 is a plan view of my latch bolt and retractor bar structure; and

Figure 6 is a side elevational view of the latch bolt and retractor bar structure shown in Figure 5.

Referring to the drawings, particularly Figures 1, 2, and 3, a spring latch structure is shown consisting generally of a cylindrical housing 11 having an outer flush plate 12 and an inner flush plate 13, the two flush plates being clamped together on the out-turned rim 14 of the housing 11 by the screw 15 in the hole 16 in the flush plate 13 and in the threaded hole 17 in the outer flush plate 12. The latch bolt 18 is shaped in the usual way with a rounded bevel on the face 19 which strikes the keeper on closing the door, and has a flat surface 20 parallel to the bolt axis on the opposite side which engages the keeper and locks the door. An auxiliary latch bolt 21 adapted to deadlock the main latch bolt when the latter is inside the keeper and the latter is depressed by striking the edge of the keeper, is provided in sliding contact with the flat face 20, a spring 22 pressing between the inner end of the housing 11 and said auxiliary latch bolt to keep the latter in extended position, the shoulder 23 abutting the inner end of the main latch bolt 18.

The main latch bolt 18 is provided with a retractor bar 24 which is rigidly attached thereto by means of the washer 25 set in the recess 26 of the latch bolt 18, a right-angled tab 27 on the washer

being provided for holding one end of the coil spring 28 whose opposite end abuts the inner end of the housing 11 to keep the latch bolt 18 outwardly extended. The retractor bar 24 extends through the housing 11 and is provided with a head 29 which is engageable by retractor fingers 30 in the lock mechanism.

My invention resides in the structure and manner of assembly of the latch bolt and the retractor bar, this assembly being used in a spring latch mechanism as above described. Referring particularly to Figures 4, 5, and 6, showing the details of the assembly of the latch bolt, retractor bar and washer, the latch bolt consists of a shaped metal piece having a generally cylindrical shape with the bevelled surface 19 and the opposite flat surface 20 following the customary shape of latch bolts. The inner end of the latch bolt 18 is recessed to form a marginal rim 31 which extends inwardly from the inner end of the latch bolt, the rim being provided with openings 34 therethrough for purposes described below. A deep slot recess 33 is centrally disposed below the base of the marginal rim 31 and is preferably provided with slightly tapered edges, the slot being longer at the top than at the bottom of the recess. A washer 25 is adapted to fit within the rim 31 and is provided with locking tabs 33 which fit into the opposite openings 34 in the marginal rim of the latch bolt. The washer 25 is also provided with a slot 35 which is centrally located and is adapted to receive the retractor bar 24. Other projections from the washer, including the guide tab 36 for the auxiliary latch bolt and the spring tab 27 may be provided on the washer. The retractor bar 24 consists of an elongated bar having an enlarged head 37 with shoulders 40 which is adapted to fit in the deep slot recess 33 in the latch bolt 18, the head being tapered at the edges to closely fit the tapered edges 32 of the slot. The retractor bar may be joined to the washer by other means than the slot and abutting shoulders.

In making the assembly, the washer 25 is slipped over the retractor bar 24 to an abutting position against the shoulders 40 of the enlarged head 37 and the head is inserted in the slot 33 in the latch bolt 18 which it fits closely, with the locking tabs 33 extending into the rim windows or openings 34. The rim 31 is rolled over adjacent the top surface of the washer 25 so that the head 37 is thrust tightly into the deep slot recess 33 and the washer is held securely against separation by the overturned rim, as shown somewhat exaggeratedly at 41.

My invention provides means for rigidly and permanently joining parts of different shapes and of different metals, thus permitting low cost manufacturing operation. My assembly of the latch bolt and retractor bar is particularly ad-

vantageous when used with latch bolts made from cast or sintered pressed metal in which no undercut portions may be formed in the forming process. The provision of the slight taper on the edges of the enlarged head 37 and in the deep slot 38 permits accurate fitting of the head in the slot when pressed together by the rolling operation which turns the rim over and against the edges of the washer 25. This assembly provides means for making a low cost latch bolt and bar with a minimum amount of hand work involved in the finishing of the parts and in the assembly.

I claim:

1. In a lock bolt structure, a latch bolt having a beveled outer end and an inner recessed end including a marginal rim extending at least partly around said inner end face, said rim having openings therethrough, and having a deep slot centrally disposed from said recessed face, said slot having its end walls tapered slightly inwardly toward the bottom of the slot; a retractor bar having an enlarged end portion with abutment shoulders, said end portion being tapered and adapted to closely fit in the deep slot of said latch bolt; a retainer washer adapted to fit within the marginal rim of said latch bolt, said washer having locking tabs extending into the openings in said rim, and said washer having a centrally disposed slot adapted to receive said retractor bar, said washer abutting said shoulders to prevent withdrawal of said bar; and the marginal rim of said bolt being rolled against the edge of said washer to hold the bolt, washer and bar in rigid assembly.

2. In a lock bolt structure, a latch bolt having a beveled outer end and an inner recessed end including a marginal rim extending at least partly around said inner end face, said rim having openings therethrough, and a retainer washer adapted to fit within the marginal rim of said latch bolt, said washer having tabs extending into the openings in said rim, some of said tabs projecting outside the limits of said bolt, and said washer being adapted to engage the enlarged end of a centrally disposed retractor bar disposed at right angles to said washer; and the marginal rim of

said bolt being rolled over the edge of said washer to hold the bolt, washer and bar in rigid assembly.

3. In a lock bolt structure, a latch bolt having a beveled outer end and an inner recessed end including a marginal rim extending at least partly around said inner end face, said rim having openings therethrough, and a retainer washer adapted to fit within the marginal rim of said latch bolt, said washer having tabs extending through the openings in said rim, and said washer being slotted to receive the shank of a centrally disposed retractor bar having an enlarged head, said bar being disposed at right angles to said washer; and the marginal rim of said bolt being rolled over the edge of said washer to hold the bolt, washer and bar in rigid assembly.

4. In a lock bolt structure, a latch bolt having an inner recessed end including a marginal rim extending at least partly around said inner end face, said rim having an opening therethrough, and having a deep slot centrally disposed from said recessed face, said slot having its end walls tapered slightly inwardly toward the bottom of the slot; a retractor bar having an enlarged end portion with abutment shoulders, said end portion being tapered and adapted to closely fit in the deep slot of said latch bolt; and a retainer washer adapted to fit within the marginal rim of said latch bolt, said washer having a tab extending into the opening in said rim, and said washer having a centrally disposed slot adapted to receive said retractor bar, said washer abutting said shoulders to prevent withdrawal of said bar; the marginal rim of said bolt being rolled against the edge of said washer to hold the bolt, washer and bar in rigid assembly.
